SNAP FASTENER INSTALLATION AND FASTENER FOR THE SAME

John C. Calhoun, West Quincy, Mass., assignor
to United-Carr Fastener Corporation, Cam-
bridge, Mass., a corporation of Massachusetts

Application February 21, 1933, Serial No. 657,787

3 Claims. (Cl. 24—203)

My invention aims to provide improvements in snap fastener attached heel lifts for heels of shoes and snap fasteners for the same.

Referring to the drawing which illustrates a preferred embodiment of my invention:

Figure 1 is a side elevation of a shoe heel and heel lift;

Fig. 2 is an enlarged bottom plan view of the heel with the lift removed to show the fastener member carried by the heel;

Fig. 3 is a plan view of the heel lift showing a fastener member attached thereto;

Fig. 4 is an enlarged section taken on the line 4—4 of Figure 1;

Fig. 5 is a section of the heel fastener taken on the line 5—5 of Fig. 2; and

Fig. 6 is a side view of the heel lift fastener member before attachment.

Referring to the drawing, I have shown a simple and efficient fastening means for detachable shoe heel structures particularly, though not exclusively, adapted for use with so-called high heels of women's shoes. In the particular structure illustrated, I have shown (Fig. 1) a conventional high heel 1 for a woman's shoe

25 having a shallow cylindrical bore 2 (Fig. 2) formed at the lower end thereof. In the bore 2 (Figs. 2 and 4) there is located a snap fastener socket member 3 which is secured in place

30 by means of a screw 4 and held against rotation by prongs 5 projecting into the material of the heel 1. The heel lift 6 of leather, rubber or the like carries a stud member 7 attached there-

35 to by attaching prongs 8, as best shown in Figs. 3, 4, and 6. The fastener members are adapted to cooperate with each other when the heel lift 6 is pressed into position against the bottom of the heel, thereby to hold the parts in predetermined assembled relation, as shown in Fig. 4.

40 I have found that it is desirable to provide fastening members which are simple in construction, durable and so arranged that the lift will be held in a predetermined relation to the heel when attached. The socket member 3 (Figs. 2 and 5) is formed from a single piece of sheet

45 metal and has a base portion 9, a pair of opposed straight sided yieldable portions or fingers 10 extending from the base in one direction and a plurality of sharp pointed attaching prongs 5 extending from the base in the opposite direction. The yieldable fingers have their free ends

50 rolled to provide suitable shoulders 12 for snap fastening engagement with the stud member 7. As illustrated, the socket member 3 is attached to the heel 1, in the bore 2, by a screw 4 pass-

ing through a hole 14 in the base and by the attaching prongs 5 which stick into the material of the heel and prevent rotation of the socket. The socket also has a pair of rigid projections 10a extending from opposite edges thereof and located adjacent to the ends of the yieldable portions 10 (Fig. 2) to provide guide means for the yieldable portions of the stud and to keep the fasteners from coming apart laterally.

10 The stud member 7 is formed from a single piece of sheet metal and has a base 15, a pair of relatively straight side portions or yieldable fingers 16 extending from a point adjacent to the center of the base in one direction and a 15 plurality of prongs 8 extending from the base in the opposite direction, as best illustrated in Figs. 3, 4, and 6. The yieldable fingers 16 of the stud member extend from inwardly bent portions 17 extending from the periphery of the 20 base toward the center. They have their free ends bent outwardly to provide shoulders 18 for cooperative fastening engagement with the shoulders 12 of the socket. The stud member is attached by the relatively long prongs 8 which 25 pass into the material of the heel lift 6 and have their ends upset, as best shown in Fig. 4.

30 My improved device is particularly useful in connection with the heels of women's shoes because it is merely necessary to bore a shallow circular hole of substantial diameter in the heel 1 and because it is necessary to use only a stud and a socket, one of which is attached to the heel and the other of which is attached to the heel lift. My improved fasteners are also par- 35 ticularly desirable because they are so constructed that they may be easily and quickly attached in the proper predetermined relation to each part so that it is a simple matter to attach the heel lift in the proper relation to the 40 heel. Furthermore, the construction of the fastener members in and of themselves cooperates to prevent relative rotation when they are en- 45 gaged and the guide projections 10a on the socket help to center the stud relative to the yieldable fingers 16 relative to the fingers 10.

50 While I have illustrated and described a preferred embodiment of my invention, I do not wish my invention is best defined by the following claims.

I claim:

55 1. A snap fastener installation of the class described comprising, in combination, parts to be

fastened together, a stud member secured to one of said parts and having projections extending outwardly therefrom and terminating in a plane substantially parallel to said part, said projections having opposed smooth edges and opposed sides formed with shoulders extending outwardly therefrom, a socket member carried by the other of said parts and having a pair of yieldable projections extending outwardly therefrom, a pair of inwardly disposed shoulders on the ends of said yieldable projections adapted to engage the shoulders of said stud member, and a pair of substantially parallel smooth rigid projections extending from said socket member and adapted to bear against the smooth edges of the projections on said stud member thereby preventing lateral movement of said stud member relative to said yieldable projections of the socket member.

2. A snap fastener installation of the class described comprising, in combination, two parts to be fastened together, a stud member secured to one of said parts, said stud member having a base, a pair only of yieldable projections extending outwardly from said base, said projections terminating in a pair of substantially parallel oppositely disposed shoulders, the side edges of said projections including the ends of said shoulders lying in a pair of parallel planes, a socket member carried by the other of said parts and having a pair of yieldable projections extending outwardly therefrom, a pair of inwardly disposed shoulders on the ends of said projections engaging the shoulders of the stud member, and a pair of relatively smooth rigid projections extending from said socket member and bearing on the edges of said projections of the stud member, thereby producing a relatively rigid relationship

and preventing lateral movement of said stud projections relative to said socket projections.

3. A snap fastener comprising a pair of members, each of said fastener members being formed from a single piece of sheet metal, one of said fastener members having a base, a pair of straight-sided and straight-edged yieldable projections extending from said base and being nearer together at their free ends than at the base, the ends of said projections being rolled outwardly away from each other to provide shoulders with cam surfaces, said fastener member having a plurality of prongs formed from the material of said base and extending away from said base in a direction opposite to said yieldable projections to engage a supporting member, the other of said fastener members having a base, a pair of yieldable projections formed from the material of said base and extending away from said base substantially at right angles to said base, each of said yieldable projections having an inwardly rolled shoulder engaging the corresponding shoulder of the first-mentioned snap fastener member, a pair of parallel projections extending away from said base adjacent to the edges of said yieldable projections and bearing against the straight edges of the yieldable projections of the first-mentioned snap fastener member, said pairs of yieldable shoulders being so proportioned that lateral motion of the stud member relative to the socket member is prevented by the relatively rigid engagement of the said projections of the socket member with the straight edges of the projections on the stud member.

JOHN C. CALHOUN.
